UNITED STATES PATENT OFFICE.

HENRY W. DE JARRETTE, OF DES MOINES, IOWA, ASSIGNOR OF ONE-HALF TO JOHN C. HOL, OF DES MOINES, IOWA.

INK DISTRIBUTOR.

Application filed February 10, 1928. Serial No. 253,387.

My invention relates to an improvement in ink distributors for printing presses.

More particularly, it is my object to provide in a printing press an auxiliary ink distributing roller so mounted and arranged as to function for more evenly properly distributing ink.

With these and other objects in view, my invention consists in the construction, arrangement and combination of the various parts of my ink distributor, whereby the objects contemplated are attained, as herein-after more fully set forth, pointed out in my claims, and illustrated in the accompanying drawings, in which:

Figure 1 is a top or plan view of a portion of a press equipped with an ink distributor embodying my invention.

Figure 2 is a sectional view of my distributor and parts of the press, as taken on the line 2—2 of Figure 1, a portion of the press being shown in side elevation.

Figure 3 is a similar view illustrating the parts in a different position.

Figure 4 is an enlarged, sectional, detail view taken on the line 4—4 of Figure 3.

Figure 5 is a sectional, detail, view taken on the line 5—5 of Figure 3; and

Figure 6 is a sectional, detail view taken on the line 6—6 of Figure 4.

I shall first describe enough of the press on which my ink distributor is used to illustrate the application of my distributor.

The press frame is indicated at 10. Slidably supported on the press is a second frame 12, which is adapted to carry the chase 14. The frame 12 and chase 14 reciprocate horizontally.

At one end of the press is an inking fountain, comprising an inclined ink plate 16 adjacent to the lower edge of which rolls the large ink roller 18.

Arranged above the path of travel of the chase 14 are the ink distributing rollers indicated generally at A.

The right-hand roller of the series A indicated at 20 is inclined from the true transverse line as shown in Figure 1.

The press has rollers 22 on which the frame 12 rolls or travels for bringing the chase 14 and the type or cuts or the like 14 therein underneath the inking rollers B.

The frame 12 carries the inking plate 26. A transverse shaft 28 is mounted in the frame and has at its ends the arms 30 which support the roller 32.

On the shaft 28 is an arm 34 to which is connected an actuating rod or the like 36.

In the operation of the press, the frame 12 moves to the left and while it is making the leftward portion of its movement, the rod 36 is actuated for moving the arm 34 for rocking the shaft 28 and moving the roller 32 from its position shown in Figure 2 downwardly until the roller 32 contacts with the large roller 18.

The roller 18 is rotated by mechanism not here particularly shown.

The roller 32 remains in contact with the roller 18 for a sufficient time to take up a supply of ink. Then the rod 36 is actuated again, and the roller 32 is returned to its position shown in Figure 3. Then when the frame 12 moves to the right, the ink on the roller 32 is distributed over the ink plate 26. As the plate 12 continues to reciprocate a new supply of ink is constantly furnished to it.

The rollers A serve to distribute this ink over the plate 26.

The purpose of the rollers A is to distribute the ink evenly over the plate 26.

When the plate 26 travels under the rollers B, they are inked.

When the frame 12 approaches the right-hand end of its stroke, the printer's chase 14 is drawn beneath the rollers B, which will then distribute ink over the type faces.

The press which has been described is in common use, and I have not attempted to describe it in detail.

There are certain defects in the operation of this press. The defect which I desire to eliminate by my present device is that where by heavy streaks of ink are left on the plate 26 and transmitted to the distributing and inking rollers.

Particularly for instance when the frame 12 reaches the end of its right-hand movement and starts back, the roller 32 leaves a transverse rib or line more heavily inked than are other parts of the ink plate 26.

It is my purpose to insure the distribution of this heavy line and other streaks of ink, which sometimes occur.

For accomplishing this purpose, I have mounted an auxiliary ink distributor, comprising a distributor roller 38 having the metal shaft 40 projecting from its ends. At 5 one end, the shaft 40 is journaled adjacent to the roller 20 in the following manner:

On the frame 10 is mounted a support 42 having on its upper end a threaded portion 44. A threaded socket 45 is adjustably 10 screwed onto the portion 44 and projects upwardly therefrom. In the upper end of the socket 45 is a spindle member 47 terminating in a yoke 49.

One end of the shaft 40 is slidably extended 15 through the yoke 49 and held in position by a key 51, as shown in Figure 4. Thus the roller is mounted at the end now under consideration for universal movement, and the shaft 40 can rotate or slide in the yoke 49.

20 The roller can be adjusted vertically by adjusting the socket 45 on the portion 44.

At the other end, the roller 38 is mounted in the following manner:

On the frame, I attach a bracket 54 (see 25 Figures 3 and 4) having a horizontally arranged boss 56. Supported on the boss 56 is a spindle 58. The bracket 54 and the various parts which it supports may be secured on either the inside or outside of the 30 press frame 10, depending on the construction of the particular press to which the device is applied.

A bell crank 60 is journaled on the spindle 58 and its upper end is provided with a 35 threaded socket 62. Screwed into the socket 62 is a rod 46. (See Figures 3 and 6.)

At the upper end of the rod 46 now under consideration is a half socket 48 which coacts with a half socket 50 (see Figure 6.) Received in the socket members 48 and 50 last 40 described is a ball 52^a. The half sockets are secured together by screws 43.

One end of the shaft 40 is extended through 45 the ball 52^a and is locked thereto by means of a screw 64.

The bell crank has a downwardly extending arm 66 having an elongated slot 68 (see Figure 2.)

Fixed to the end of the shaft 28 and preferably 50 projecting outwardly therefrom is an arm 70 having a plurality of threaded openings 72 (see Figures 2 and 4.)

The arms 66 and 70 are connected by a two-part link consisting of the socket member 74, which is pivoted to the arm 70 by means of a shouldered screw or the like 76, having threaded into it one end of a short rod 78. Extended through the rod 78 is a bolt or the like 80, which can freely rotate 60 in the rod 78 (see Figure 5.)

On the bolt 80, which thus serves as a pin 65 tle is an annular flange or shoulder 82. The other end of the bolt 80 is extended through the arm 66 and has a nut 86, by which the arm 66 can be frictionally gripped against

the shoulder 82 for locking the rod 78 to the arm 66 at any position in the length of the slot 68.

I shall now explain the actuation of the 70 roller 38.

When the roller 32 is swung to its lowermost position as shown in Figure 2, the roller 38 will be swung to its left-hand position illustrated for instance in full lines in Figure 1.

When the roller 32 is swung back to its upper position shown in Figure 3, the operation of the parts is such that the roller 38 is swung from its position shown in Figure 1 to its position shown in dotted lines in that 80 figure, where it contacts with the roller 32, so that as the roller 32 is rotated by the movement of the plate 26 thereunder, the roller 38 will also be rotated by the roller 32. In the full line position, the roller 38 85 will be rotated by the roller 20.

The contact of the roller 38 with the roller 32 will help to smooth out and distribute the ink on the roller 32.

When the roller 38 is in its position shown in Figure 1, it will contact with the roller 20. The roller 20 is rotated by mechanism not here shown, and while it is in contact with the roller 38, the roller 38 will help to smooth out and distribute any heavy ink 90 streak on the roller 20.

Thus when the roller 38 is in one position, it contacts with a roller extending in a proper transverse line across the press, and when it is in its other position shown by full lines 100 in Figure 1, it will be inclined from the transverse, and will be parallel with and contacting with the roller 20.

On account of the peculiar mounting of the end of the roller 38 shown at the right-hand part of Figure 4, the left-hand of the roller may swing on the member 58 as a center without any binding of any of the parts.

I find that in actual use, the use of the roller 38 serves to produce a much more even and complete distribution of the ink, than is possible without it, and that the streaks which are otherwise left are almost entirely eliminated.

Particularly in this respect, attention is called to the fact that when the roller 32 is in contact with the fountain roller 18 and the two are rotated, a little ridge or body of ink is formed along their line of engagement. When the roller 32 is swung from its position shown in Figure 2 toward its position shown in Figure 3, it carries a ridge or thickened line of ink, which where my invention is not used, is deposited on the plate 26 and is never entirely eliminated by the distributing 115 rollers.

It will be noted that the roller 38 is of a diameter different than that of the roller 32.

It is therefore obvious that when the rollers 32 and 38 are in their positions shown in 120 125 130

Figure 3, this heavy or thickened line of ink will be deposited on the roller 38 and back again at several new places on the roller 32. This is assuming that the roller 38 is of 5 smaller diameter than the roller 32. Consequently there will be a considerable distribution and smoothing out of this thickened line as it is being transferred to the plate 26. When the roller 38 moves over to engagement 10 with the roller 20, the thickened line or lines which will have been deposited on the roller 38 will be deposited in several lines on the roller 20, and this further contributes to the ultimate even distribution of the ink.

15 In actual practice, where my auxiliary distributor is not used, I find that the roller 32 tends to distribute the thickened line on the plate 26 at the same place by successive operations, so that the unevenness in the distribution 20 of the ink is increased the longer the press runs. This is due to the periodic operations of the press, which have the effect of timing the roller 32.

It will, of course, be understood that some 25 changes may be made in the details, of the construction and arrangement of my ink distributor without departing from the real spirit and purpose of my invention, and it is my intention to cover by my claims any modified 30 forms of structure or use of mechanical equivalents, which may be reasonably included within their scope.

I claim as my invention:

1. In a press having a plurality of distributing rollers, including one roller arranged at an angle to the transverse and having a swinging inking roller, an auxiliary distributing roller mounted at one end for universal and for rotary and limited sliding movement, means for moving the other end of said auxiliary roller for causing it in one position of its movement to contact with said inclined distributing roller in substantial parallelism therewith and in another position 45 of its movement to contact with said swinging roller in parallelism therewith.

2. In a device of the class described, the

combination of a press structure having an ink distributing roller inclined from the transverse, and an ink roller mounted to swing from one position to another, an auxiliary inking roller of diameter less than that of the ink roller, means for moving said auxiliary inking roller, whereby in one position of its movement it contacts lengthwise with 50 said inclined roller and in another position of its movement it contacts lengthwise with 55 said swinging roller.

3. In a device of the class described, the combination of a press structure having an ink distributing roller inclined from the transverse and an ink roller mounted to swing from one position to another with an auxiliary roller of a diameter different from that of the ink roller, means for actuating 60 said auxiliary roller for bringing it into lengthwise contact with said inclined roller and holding it there for a limited time and then moving the auxiliary roller to position for contacting with said swinging roller in 65 one position of the swinging roller and holding the auxiliary roller in such contact for a limited time.

4. In a device of the class described, the combination of a press structure having an ink distributing roller inclined from the transverse and an ink roller mounted to swing from one position to another with an auxiliary roller, means for actuating 70 said auxiliary roller for bringing it into lengthwise contact with said inclined roller and holding it there for a limited time and then moving the auxiliary roller to position for contacting with said swinging roller in one 75 position of the swinging roller and holding the auxiliary roller in such contact for a limited time, said means including means for journaling one end of the auxiliary roller for universal movement and for rotary and limited sliding movement, and means for mounting the other end of said roller for intermittent, reciprocatory swinging movement.

Des Moines, Iowa, February 6, 1928.

HENRY W. DE JARNETTE.
